UNITED STATES PATENT OFFICE.

WILHELM GOTTHILF SCHRÖDER, OF LÜBECK, GERMANY.

APPARATUS FOR HOMOGENIZING MILK AND OTHER LIQUIDS.

1,140,289.

Specification of Letters Patent.

Patented May 18, 1915.

Application filed November 26, 1913. Serial No. 803,187.

To all whom it may concern:

Be it known that I, WILHELM GOTTHILF SCHRÖDER, manufacturer, a citizen of the free town of Lübeck, in the Empire of Germany, and resident of Lübeck, Germany, have invented new and useful Apparatus for Homogenizing Milk and other Liquids, of which the following is a specification.

The present invention relates to a new apparatus for homogenizing liquids between surfaces pressed against each other.

When milk is pressed between two carefully ground surfaces, resembling the cones of a valve and pressed against each other, the distance from the seat of the valve to the cone of the valve is a constant figure at a given pressure and a given mean diameter of the cone. This figure determines the degree of the homogenization as liquid particles which are of a diameter smaller than the distance between valve seat and valve cone can, of course, be no more disintegrated between the homogenizing surfaces. The fundamental principle, which has been employed in the new apparatus consists in obtaining this gap between the homogenizing surfaces as small as possible. This can, on the one hand be obtained, by employing very large surfaces, which, however, in practice would offer very great disadvantages, or, several seats and cones may be arranged, as shown in the accompanying drawing, above each other, through which the liquids to be homogenized is then forced. It is obvious, that at a given pressure and at a given diameter the distance between the several seats will be only a fraction of the distance between the seat and cone of an apparatus with one homogenizing surface only. For instance, if in an apparatus employing only two working surfaces, the distance between these surfaces were 0.01 mm., then at the same pressure and diameter the distance between the working surfaces in the present invention, employing, for instance, five pairs of conical members, would be only 0.01:5 or 0.002 mm. Therefore the present apparatus must, under otherwise equal conditions, produce a much finer product or in other words,

must have a higher effect at the same diameter of the homogenizing surfaces and at a lower pressure than an apparatus with one surface only.

Figure 1 in the accompanying drawing is 55 a longitudinal section through the new apparatus. Fig. 2 is a cross section through the same. Fig. 3 is a longitudinal section through the rotating type of machine, and Fig. 4 is a cross section taken on the line 60 4-4 of Fig. 3. The apparatus consists of the mouthpiece *a*, which is screwed to the delivery pipe of a homogenizing machine or a pressure vessel. In this mouthpiece are disposed the circular members *b* and *c* 65 which are carefully ground against each other. The members *b* each carry two conical working surfaces on their inner side. These two working surfaces fit accurately the two conical working surfaces carried 70 by each of the members *C* on their outer side. The members *b* fit into the large bore of the mouthpieces with a snug fit. The top member *d* is provided with a stem *d'*, preferably of a cross-shaped section and 75 serving as a guide for the several members. The liquids to be homogenized enter at *a* into the apparatus and a given quantity is forced to travel between each of the several working surfaces collecting in the gutters *e* which are cut into the mouthpiece, and finally passing into the chamber *f* of the casing *g*, where they can then escape freely through the tube *h*. The several homogenizing surfaces are pressed against each 80 other in a similar manner as with a valve by means of the screw spindle *i*, which is packed in the gland *k*, and the position of which can be fixed by means of a lock nut *l*.

In the modified form shown in Figs. 3 90 and 4, the conical members may be made to revolve. The spindle *d'* to which the conical members *c* are keyed is driven by the power wheel *m*, the conical members *b* at the same time being prevented from rotation by the guide or lug *n*. The shaft *l'* 95 is rotatable in the bearing which is adjustable lengthwise by movement of the wheel *O*. A lock nut *l* is provided to prevent rotation of the adjusting wheel.

I claim:

1. In a homogenizing apparatus, the combination with a casing, of two series of co-acting working members carrying double working surfaces, located within said casing, the members of each series adapted to be placed in alternate relation with the members of the other series.
2. In a homogenizing apparatus, the combination with a casing, of two series of co-acting working members carrying double working surfaces, located within said casing, the members of each series adapted to be placed in alternate relation with the members of the other series, and further adapted to space apart the members of the other series from one another.
3. In a homogenizing apparatus, the combination with a casing, of a series of equal sized working members carrying double working surfaces, located within said casing, and a second series of equal sized co-acting working members carrying double working surfaces, the members of each series adapted to be placed in alternate relation with the members of the other series.
4. In a homogenizing apparatus, the combination with a casing, of a series of equal sized working members carrying double working surfaces, located within said casing, and a second series of equal sized co-acting working members carrying double working surfaces, the members of each series adapted to be placed in alternate relation with the members of the other series and further adapted to space apart the members of the other series from one another.
5. In a homogenizing apparatus, the combination with a casing carrying internal longitudinal grooves, of two series of co-acting working members located within said casing.
6. In a homogenizing apparatus, the combination with a casing carrying internal longitudinal grooves, of two series of co-acting working members, the members of either series being placed in alternate relation with the members of the other series.
7. In a homogenizing apparatus, the combination with a casing carrying internal longitudinal grooves, of two series of co-acting working members, the members of either series being placed in alternate relation with the members of the other series, said members being adapted to space apart the members of the other series from one another.
8. In a homogenizing apparatus, the combination with a casing, of a series of ring-shaped working members carried within said casing, a second series of internally apertured coacting working members, the members of the two series being placed in alter-

nate relation with each other, and a longitudinally-channelled guide member passing through the apertures of the members of said second series.

9. In a homogenizing apparatus, the combination with a casing, of a series of ring-shaped working members carried within said casing, a second series of internally apertured coacting working members, the members of the two series being placed in alternate relation with each other, a longitudinally-channelled guide member passing through the apertures of the members of said second series, a cap carried by said guide member adapted to transmit pressure to the working members, and means for applying pressure to said cap.

10. In a homogenizing apparatus, the combination with a casing carrying longitudinal grooves, of a series of ring-shaped working members carried within said casing, carrying interiorly two symmetrically disposed working surfaces, a second series of internally apertured coacting working members carrying exteriorly two symmetrically-disposed working surfaces, the members of each series being placed in alternate relation with, and adapted to space apart, the members of the other series, a longitudinally-channelled guide member passing through the apertures of the members of said second series, a cap carried by said guide member, adapted to transmit pressure to the working members, and means for applying pressure to said cap.

11. In a homogenizing apparatus, the combination with a casing provided with internal longitudinal channels, of a series of rotary working members located within said casing, a rotatable shaft adapted to rotate said rotary working members, a second series of non-rotating co-acting working members in alternate relation with the members of said first mentioned series, and means for rotating said shaft.

12. In a homogenizing apparatus, the combination with a casing provided with internal longitudinal channels of a series of internally apertured rotary working members located within said casing, a rotatable shaft adapted to rotate said rotary working members, a second series of internally apertured non-rotating co-acting working members in alternate relation with the members of said first mentioned series, said members of each series being movable axially and adapted to space apart the members of the other series from one another, means for adjusting the spacing apart of said members, and means for rotating said shaft.

13. In a homogenizing apparatus, the combination with a casing provided with

internal longitudinal channels, of a series of internally apertured rotary working members located within said casing, a rotatable shaft adapted to rotate said rotary working members, a second series of internally apertured non-rotating co-acting working members in alternate relation with the members of said first mentioned series, said members of each series being movable axially and adapted to space apart the members of the other series from one another, means for adjusting the spacing apart of said members, means for rotating said shaft, means for

dogging said members of said first mentioned series by said rotating shaft, and 15 means for preventing rotation of said members of said other series.

In testimony, that I claim the foregoing as my invention, I have signed my name in presence of two witnesses, this 12th day of 20 November 1913.

WILHELM GOTTHILF SCHRÖDER.
